COOKING GRILL

William H. Nosis, 815 Queen St., Owosso, Mich. 48867

Filed May 15, 1968, Ser. No. 11,942

Term of patent 14 years

Int. Cl. D7—04

U.S. Cl. D81—10

FIG. 1

FIG. 5

FIG. 2

FIG. 4

FIG. 3

FIGURE 1 is a perspective view of a cooking grill, showing my new design;

I claim:

The ornamental design for a cooking grill, as shown.
